UNITED STATES PATENT OFFICE.

HENRY FATTON, OF NEW YORK, N. Y.

DESIGN FOR A BOX.

SPECIFICATION forming part of Design No. 24,502, dated July 23, 1895.

Application filed June 11, 1895. Serial No. 552,485. Term of patent 14 years.

To all whom it may concern:

Be it known that I, HENRY FATTON, a citizen of the United States, residing in the city, county, and State of New York, have invented a new and original Design for Boxes; and I do hereby declare that the following is a full, clear, and exact description of the same, reference being had to the accompanying drawing, forming part thereof, which represents a box of my novel design.

My design consists mainly of the novel form of the interior of the box, which is divided into compartments of the general configuration of a "dumb-bell."

The external form of the design illustrated is rectangular, and the interior compartments

(of which there are in this case three) are, as stated, shaped in plan somewhat like a dumb-bell with pear-shaped ends and a constructed middle portion. Between adjoining compartments and between the outside compartments and the sides of the box are elongated spaces, as shown.

I claim as my invention—

The design for a box substantially as herein shown and described.

In testimony whereof I have hereunto set my hand this 8th day of February, 1895.

HENRY FATTON.

In presence of—

CLARENCE L. BURGER,
HENRY A. RUBINO.
